UNITED STATES PATENT OFFICE.

DANIEL E. SCRAFFORD, OF PEORIA, ILLINOIS, ASSIGNOR, BY MESNE ASSIGNMENTS,
TO WILLIS ELECTRIC METER COMPANY, OF CHICAGO, ILLINOIS, A CORPORATION
OF ILLINOIS.

REGISTER.

950,160.

Specification of Letters Patent. Patented Feb. 22, 1910.

Application filed August 25, 1906, Serial No. 331,957. Renewed January 3, 1910. Serial No. 536,171.

To all whom it may concern:

Be it known that I, DANIEL E. SCRAFFORD, a citizen of the United States, residing at Peoria, in the county of Peoria and State of Illinois, have invented certain new and useful Improvements in Registers; and I do hereby declare that the following is a full, clear, and exact description of the invention, which will enable others skilled in the art 10 to which it appertains to make and use the same.

This invention relates to registers for meters, and refers more particularly to that class of registering devices in which the 15 counting and indicating mechanism operates by an instantaneous or snap movement to record the measurement of the meter.

The object of my invention is to provide a simple and substantial register of the 20 above class in which the power required to operate the same is uniform at all times and which requires no increase in power at the time the change in the recording mechanism is effected,—and my invention has other 25 features of improvement which will be fully set out in the following description and particularly pointed out in the claims following and forming a part of this specification.

30 In the accompanying drawings, which illustrate my invention, and in which similar reference characters indicate similar parts in the several views, Figure 1 is a front view of the top portion of a common gas meter showing a face view of a register containing my improvements; Fig. 2 a top view of a register constructed in accordance with my improvements; Fig. 3 a sectional view on the line $a-a$ of Fig. 2 looking toward the rear plate showing the 35 parts thereon just prior to the moment of operating the recording mechanism; Fig. 4 a sectional view on the line $a-a$ of Fig. 2 looking toward the front plate of the register showing the recording mechanism; and Fig. 5, a fragmentary view showing a modification of the construction shown in Figs. 2 and 3.

The front and rear plates 1 and 2 respectively are spaced a suitable distance apart and held together by means of the posts 3, and form bearings for the operative parts of the register. The shaft or spindle

4 which is connected to and driven by the operating diaphragms of the meter in the usual manner has a hand 5 fixedly held on the front end thereof which turns around a dial 6 on the face plate 7 which is suitably secured to the front plate of the register, and each revolution of the said hand represents the passage of a comparatively small volume of gas through the meter, which in the register herein shown and described is two cubic feet.

Upon the shaft or spindle 4, intermediate of the plates 1 and 2 is a worm 8 which meshes with an elongated worm gear 9 fixed on the shaft 10 which extends parallel with the plate 2 and is journaled in the bracket bearings 11 secured onto the rear plate 2. This shaft 10 is adapted for a limited longitudinal movement in the bearings 11 and the worm gear 9 is elongated as aforesaid so as to remain in mesh with the worm 8 in every position of the longitudinal movement of the shaft 10.

Upon the shaft 10 is a spur gear 12 which meshes with a Geneva gear 13 on the shaft 15, and the shaft 15 is journaled in the bracket bearings 16 secured onto the rear plate 2. The counter mechanism of this register is of the common type comprising toothed wheels 12, 13 and 14 on the shafts 15, 16 and 17 which said wheels are arranged to operate the Geneva gears 18, 19 and 20 respectively which are carried respectively on the shafts 16, 17 and 21. This counter mechanism is arranged in the usual manner, and each Geneva gear is constantly locked against movement by means of its operating one toothed wheel and it requires ten revolutions of each one toothed wheel to effect one revolution of the Geneva wheel which it engages. The register herein shown is what is known as direct reading and the count thereof is indicated by the usual numbered dials 22, 23 and 24 on the shafts 16, 17 and 21 respectively, the numerals of which said dials appear, one at a time, through their respective sight openings 25, 26 and 27 in the face plate 8, the front plate 1 being cut away as shown back of said openings. The dials 22, 23 and 24 indicate hundreds, thousands, and ten thousands respectively and one step of each dial represents the passage of one hundred, one thousand and ten thousand cubic feet respectively through the meter. Additional dials may be used if desired to register higher amounts.

On the shaft 15 is a spur gear 28 which

meshes with the worm 29 on the shaft 10 so that when the shaft 10 is rotated the worm 29 tends to rotate the spur gear 28.

- For the purpose of delaying the operation 5 of the counter mechanism until the unit of volume indicated by the next change in the recording mechanism has just passed through the meter, and for the purpose of rendering the operation of the indicating mechanism 10 instantaneous, the shaft 16 is arranged to gradually shift longitudinally during the rotation thereof so that the worm 29 imparts no movement to the spur gear 28 until the end of the revolution of said shaft 10 15 when the shaft is returned to the initial position with a snap movement which turns the spur wheel 28 and operates the counter mechanism. This is effected by providing the shaft 10 with a circular cam 30 which 20 has the inclined face thereof parallel with and equal to the pitch of the worm 29, there being an abrupt offset 31 between the highest and lowest portions of the working face of the said cam 30. This cam rides against 25 the inclined face of a corresponding inverted stationary cam 32 so that as the shaft 10 rotates, the working face of the cam 30 rides against the working face of the cam 32, shifting the shaft 10 and worm 29 there- 30 on longitudinally in the direction indicated by the arrow in Fig. 3 so that the thread of the worm merely moves through the teeth of the spur gear 28 and holds said gear stationary until the offset 31 of the cam 30 35 passes the corresponding offset of the cam 32 when the shaft 10 is free to return to the initial position and turn the spur gear 28.
- Numerous means may be employed for returning the shaft 10 to the initial position. 40 In Figs. 2 and 3, I have shown a bracket 38, pivoted on the spindle 39 and provided with a depending portion 40 which bears against the rounded projecting left end of the shaft 10. The bracket 38 supports a weight 37, 45 and as the shaft 10 is moved longitudinally toward the left by the cam members, the bracket with the weight is swung, and when the cam 31 reaches the offset of the corresponding cam 32, the weight bracket is released and swings to its normal position to quickly return the shaft 10 to its initial position. In place of the weight, its mechanical equivalent, such as a spring may be used. 50
- In Fig. 5, I have shown a somewhat modified arrangement of the cam mechanism and returning mechanism. Instead of having the cam member 30 engage a similar stationary cam member 32, I provide a roller 43 pivoted to the frame 2 and in position to be engaged by the cam surface of the cam member 30. As this cam member rotates over the roller, the shaft 10 is moved to the left and suddenly released, when the offset 31 60 leaves the roller. To insure returning of

the shaft to initial position, a cam member 33 is secured to the shaft, which has a cam surface substantially similar to that of the member 30. A roller 44 engages the cam surface of member 33 and is pivoted to the frame 2. When the offset 31 leaves the roller 43, the ridge 33' of the cam member engages with roller 44 and quickly forces the shaft 10 back to its initial position. As shown in Fig. 3, the shaft 10 is inclined, 70 and the angle of inclination may be sufficient so that the force of gravity will tend to return the shaft 10 to its initial position after an upward longitudinal movement thereof and the form of return mechanism 75 shown in Fig. 5 is preferable where an inclined shaft is used. If the shaft does not return immediately by the force of gravity and sticks, the cam ridge 33' striking the roller 44 starts the shaft 10 so that it will 80 return to its normal position.

Many other modified arrangements are also possible which will still come within the scope of my invention, and I desire to secure the following claims by Letters Patent. 90

What I claim is:

1. In a registering device, the combination of a continuously driven rotary member, means for reciprocating said member, and calculating mechanism operated by said member. 95

2. In a registering device, the combination of a continuously driven member, means controlled by the continuous movement of said member to reciprocate said member, and calculating mechanism operated by the reciprocation of said member. 100

3. In a registering device, the combination of a rotary member, means controlled by the rotation of said member to reciprocate said member, and calculating mechanism operated by the reciprocation of said member. 105

4. In a registering device, the combination of a rotary member, means for gradually displacing said member during a predetermined amount of rotation thereof, means for returning said member to its initial position at the end of the said predetermined amount of rotation and calculating mechanism operated by the return movement of said member. 110

5. In a registering device, the combination of a rotary member, means for causing the rotation of said member to displace said member, means for returning the said member to its initial position at the end of every revolution and calculating mechanism operated by the return movement of said member. 115

6. In a registering device, the combination of a continuously driven member, a stationary member means on the continuously driven member engaging the stationary member for reciprocating said continuously 120

125

130

driven member and calculating mechanism operated by the reciprocation of said member.

7. In a registering device, the combination of a rotary member, a stationary member, means on the rotary member engaging the stationary member for gradually displacing said rotary member, means for returning the rotary member to its initial position at the end of each revolution and calculating mechanism operated by the return movement of said rotary member.

8. In a registering device, the combination of a rotary member, means for causing the rotation of said member to displace said member axially, means for returning the said member to its original position at the end of every revolution, calculating mechanism operated by the return movement of said member and means on the said rotary member for holding the calculating mechanism inoperative during the gradual displacement of the rotary member.

9. In a registering device, the combination of a rotary member, a spiral cam having a step down offset from the highest point to the lowest point in the working face thereof, means engaging the said cam for displacing the rotary member axially, means for returning the rotary member to its initial position when the aforesaid means which engages the cam moves past the offset in the face thereof and calculating mechanism operated by the return movement of the rotary member.

10. In a registering device, the combination of a rotary member provided with a spiral cam having a step down offset from the highest point to the lowest point in the working face thereof, means engaging the working face of said spiral cam for gradually displacing said rotary member, means for returning said rotary member to the initial position when the means which engages the cam moves past the offset in the working face thereof and calculating mechanism operated by the return movement of said rotary member.

11. In a registering device, the combination of a shaft, a spiral cam, means for engaging the working face of the cam for gradually displacing the shaft, an abrupt offset in the face of said cam adapted to suddenly release the shaft while rotating, means for returning the shaft to the initial position while rotating, and calculating mechanism operated by the return movement of the shaft.

12. In a registering device, the combination with calculating mechanism, of a gear connected to operate said calculating mechanism, a rotary spiral member engaging the aforesaid gear, means for gradually shifting the said spiral member during the rotation thereof for holding the aforesaid

gear inoperative and means for returning the said spiral member to the initial position at the end of every revolution for turning the aforesaid gear for operating the calculating mechanism.

13. In a registering device, the combination with calculating mechanism of a spur gear arranged to operate the calculating mechanism, a rotary worm engaging the spur gear, means for shifting the worm axially during the rotation thereof to prevent the rotation thereof from operating the spur gear, means for returning the rotary worm to the initial position at the end of each revolution for rotating the spur gear to operate the calculating mechanism.

14. In a registering device, the combination with calculating mechanism of a spur gear for operating the calculating mechanism, a rotary part, a worm on the rotary part in mesh with the spur gear, a spiral cam for gradually shifting the rotary part and worm thereon axially during the rotation thereof to prevent the rotation of the worm from operating the spur gear, means for returning the rotary part and worm thereon to the initial position at the end of every revolution for imparting movement to the spur gear to operate the calculating mechanism.

15. In a registering device, the combination of a rotary member, a spiral cam for gradually displacing the rotary member, an abrupt offset in the said cam to permit return of the rotary member to its initial position at the end of each revolution, a second spiral cam for locking the rotary member against axial vibration, the said second cam being arranged to permit advance movement of the rotary member as the said member is rotated, and to force the rotary member to the initial position at the end of each revolution and calculating mechanism operated by the return movement of the rotary member.

16. In a registering device, the combination of a rotary shaft, a cam for shifting the shaft longitudinally as the shaft is rotated, a second cam arranged to prevent longitudinal displacement and permit gradual advance for the shaft and calculating mechanism operated by the longitudinal movement of the rotary shaft.

17. In a registering device, the combination of a rotary member, means for gradually shifting the said rotary member axially during the rotation thereof, means for forcing the rotary member to the initial position at the end of every revolution and calculating mechanism operated by the return movement of the rotary member.

18. In a registering device, the combination of a rotary member, calculating mechanism connected with said rotary member, means for causing combined rotary and

bodily movement of said member at a speed to prevent operation of the engaged calculating mechanism, and means for causing only bodily movement of said member to thereby cause operation of the engaged calculating mechanism.

19. In a registering device, the combination of a spur gear, calculating mechanism operated upon rotation of said spur gear, a worm gear meshing with the spur gear, means for continuously rotating said worm gear, means for causing bodily movement of said worm gear in one direction during ro-

tation thereof, the speed of rotation and bodily movement being such that the spur gear will not be rotated, and means for causing return bodily movement of said worm gear at increased speed so that the spur gear will be rotated and the calculating mechanism operated.

In testimony whereof I have affixed my signature, in presence of two witnesses.
